UNITED STATES PATENT OFFICE.

EZRA DIXON, OF BRISTOL, RHODE ISLAND.

TOP-ROLL SADDLE.

1,087,734.

Specification of Letters Patent. Patented Feb. 17, 1914.

Application filed November 20, 1912. Serial No. 732,449.

To all whom it may concern:

Be it known that I, EZRA DIXON, a citizen of the United States, residing at Bristol, in the county of Bristol and State of Rhode Island, have invented a new and useful Improvement in Top-Roll Saddles, of which the following is a specification.

This invention pertains to certain new and useful improvements in top roll saddles, used to hold the top rolls in contact with the drawing rolls of spinning machines, and the primary object of the invention is to provide means for positively limiting movement between the top and bottom saddles, so that after adjustment of the saddles for spinning of short or long fibered staple, accidental movement of the saddles with relation to each other is prevented.

In the drawings—Figure 1 is a fragmentary side elevation, partly in section of a spinning machine, illustrating the present invention applied thereto, the saddle being shown for use in spinning short fibered staple. Fig. 2 is a similar view wherein the saddle is shown for use in spinning long fibered staple. Fig. 3 is a section on the line 3—3 of Fig. 1, and Fig. 4 is a view similar to Fig. 3, showing the saddles in reversed position, ready for disconnection or adjustment.

The invention consists of a bottom saddle 1 which is formed with an upstanding arm 2 that is slotted at 3 the latter leading into an annular aperture 4, the aperture being for reception of the shank 5 of the top saddle 6. The shank 5 is preferably circular in cross section so as to be conformably received in the aperture 4, as depicted in Fig. 3 of the drawings. The shank 4 is provided with a series of spaced depending lugs 7, which, when the top saddle is inverted, are capable of passing through the slots 3, as shown in Fig. 4 of the drawings. When the saddles occupy the relative positions shown in Figs. 1 and 2, of the drawings, it will be evident that the lugs 7 which engage on opposite sides of the arm 2 will restrict the sliding movement of the saddles. To change the relative positions of the saddles, they are moved so that the lugs 5 register or align with the slot 3 of the arm 2, whereupon by sliding movement, the saddles may be adjusted to either of the positions shown in Figs. 1 or 2, or they may be disengaged from one another, as desired.

In spinning short fibered staple, the bottom saddle rests on the two back rolls A, as shown in Fig. 1, and in spinning long fibered staple the bottom saddle rests only on the back roll A. With the present invention the two saddles are limited in their relative movements so that when the bottom saddle is adjusted for either position it cannot be accidentally moved to the other position. This absolutely prevents wrong adjustment of the saddles after they have been once set for the desired staple to be spun. It oftentimes happens that a careless operator in piecing up will move the bottom saddle to the wrong position, but with the present invention this objection is completely eliminated, and positive assurance given against accidental or careless movement of one saddle with relation to the other.

Having thus described my invention, I claim as new and desire to secure by Letters Patent:

1. In a device of the type described, a top saddle and a bottom saddle adjustable relative to the top saddle, and means to limit said saddles against relative longitudinal movement after adjustment thereof, said means allowing adjustment or disengagement of the saddles when one of the latter is inverted relative to the other.

2. In a device of the type set forth, a bottom saddle formed with an upstanding arm which is slotted and which has an aperture at the base of the slot, a top saddle formed with a shank receivable through the aperture of said arm and having a series of spaced lugs which are capable of being slid through the slot, said lugs being for engagement with opposite sides of the arm.

3. In a device of the type set forth, a bottom saddle formed with an upstanding arm which is slotted, and a top saddle formed with a shank which is slidable through the slot, and means on the shank to prevent disengagement of the saddles, when the latter occupy normal positions.

4. In combination with a top and bottom saddle, means carried by one saddle and being slidably engaged with the other saddle to connect the saddles, and a series of means carried by the last named saddle for co-operation with opposite sides of the first-named means to limit relative longitudinal movements of the saddles.

5. In combination with a top and bottom saddle, coöperating devices carried by the saddles, said devices in one position limiting the saddles against longitudinal movement and in another position permitting said saddles to be moved longitudinally with respect to each other.

In testimony whereof I have signed my name to this specification in the presence of two subscribing witnesses.

EZRA DIXON.
